(57) **CLAIM**

The ornamental design for a shark head shaped article-carrying pack, as shown and described.

DESCRIPTION

FIG. 1 is a front perspective view of a shark head shaped article-carrying pack in accordance with a first embodiment of the present invention;

FIG. 2 is a rear perspective view of FIG. 1;

FIG. 3 is a front elevational view of FIG. 1;

FIG. 4 is a rear elevational view of FIG. 1;

FIG. 5 is a right side elevational view of FIG. 1;

FIG. 6 is a left side elevational view of FIG. 1;

FIG. 7 is a top plan view of FIG. 1;

FIG. 8 is a bottom plan view of FIG. 1;

FIG. 9 is a front perspective view of a shark head shaped article-carrying pack in accordance with a second embodiment of the present invention;

FIG. 10 is a rear perspective view of FIG. 9;

FIG. 11 is a front elevational view of FIG. 9;

FIG. 12 is a rear elevational view of FIG. 9;

FIG. 13 is a right side elevational view of FIG. 9;

FIG. 14 is a left side elevational view of FIG. 9;

FIG. 15 is a top plan view of FIG. 9;

FIG. 16 is a bottom plan view of FIG. 9;

FIG. 17 is a front perspective view of a shark head shaped article-carrying pack in accordance with a third embodiment of the present invention;

FIG. 18 is a rear perspective view of FIG. 17;

FIG. 19 is a front elevational view of FIG. 17;

FIG. 20 is a rear elevational view of FIG. 17;

FIG. 21 is a right side elevational view of FIG. 17;

FIG. 22 is a left side elevational view of FIG. 17;

FIG. 23 is a top plan view of FIG. 17; and,

FIG. 24 is a bottom plan view of FIG. 17.

The broken lines depicting structural elements in the drawing views have been shown for the purpose of illustrating portions of the shark head shaped article-carrying pack that form no part of the claimed design.
